UNITED STATES PATENT OFFICE.

HENRY O. ENGSTROM, OF BRIDGEPORT, CONNECTICUT, ASSIGNOR TO DE JUR PRODUCTS CO., OF NEW YORK, N. Y.

JACK PLUG.

Application filed March 6, 1925. Serial No. 13,581.

This invention relates to a jack plug of the telephone type, useful for a variety of purposes, but especially adapted for use in connection with telephone jacks or plug receptacles ordinarily employed in radio apparatus.

Objects of the invention are to provide a jack plug of the present character which will be an improvement generally over all some-
10 what similar plugs heretofore known; which will be simple and practical in construction, the plug consisting of a minimum number of parts; which can be very economically manufactured; and which will be durable
15 and dependable in use.

A further object is to provide a jack plug of the telephone type the handle of which consists of a single piece of ordinarily molded insulating material having a con-
20 ducting nut incorporated therein.

A further object is to provide a jack plug having a one-piece insulating handle as stated, and also having connectors and contact portions of simple and improved construction adapted to be associated with said one-piece insulating handle.

A still further object is to construct the one-piece insulating handle so that each of the elements of said conductors and con-
30 nectors can be separately assembled there-
with and disassembled therefrom, and to construct said insulating handle so that it can cooperate with the remainder of the plug structure in locating all of the conductors
35 and connectors thereof, whereby the com-
pleted plug can be composed of but a minimum number of conductors, connectors and insulating members all associated in simple and unique manner.

With the above objects in view, as well as others which will appear as the specification proceeds, the invention comprises the construction, arrangement and combination of parts as now to be fully described and as
45 hereinafter to be specifically claimed, it being understood that the disclosure herein is merely illustrative and meant in no way in a limiting sense, changes in details of construction and arrangement of parts being
50 permissible so long as within the spirit of the invention and the scope of the appended claims.

In the accompanying drawing forming a part of this specification,

Fig. 1 is a top or bottom plan view of an 55 assembled plug in which the features of the invention are incorporated, and having conductors inserted therein and ready for use;

Fig. 2 is a central, longitudinal, horizontal sectional view of the plug of Fig. 1, dis- 60 closing one of the conductors removed;

Fig. 3 is a sectional view as on line 3—3 in Fig. 2;

Fig. 4 is an end view of the handle of the plug as seen from the right in Figs. 1 and 2; 65

Fig. 5 is a view corresponding with the showing of Fig. 4, but disclosing the spring connectors associated with the handle;

Fig. 6 is a fragmentary sectional view as on line 6—6 in Fig. 2; and 70

Fig. 7 is a detail of all of the parts of the plug disassembled, suggesting the manner of assembly.

With respect to the drawing, 10 denotes the handle of the improved plug which consists of a single piece of suitable insulating material. This handle is ordinarily molded and includes passages and recesses of pecu- 75 liar construction in its interior.

Numerals 11 and 12 denote spaced apart, 80 longitudinal passages extending through the handle 10, the end portions 13 and 14, respectively, of said passages being enlarged to better receive cord tips.

The opposite end 15 of the handle has a 85 central recess 16 at the base of which is a conducting nut 17. The nut 17 is desirably molded in the material of the handle between the passages 11 and 12 and has a threaded interior 18 with which the recess 90 16 is adapted to communicate.

The recess 16 is preferably tubular and of diameter slightly greater than the diameter of the nut 17, and diametrically opposite portions of the recess, in the direction 95 of the width of the handle, have substantial communication with the adjacent end portions of the passages 11 and 12, as indicated at 19 and 20, respectively.

Numeral 21 represents a spring connector 100 of L-shape having a long arm 22 adapted to enter the passage 11 and a short arm 23 adapted to enter the recess 16 to lie against the adjacent face of the conducting nut 17. The arm 23 is shaped to fit the recess 16 and adjacent recess 19 so that a part of said arm 105 23 can lie against said nut 17 and a part thereof can lie in the communicating way

19 between the recess 16 and passage 11, while the arm 22 of said spring connector extends into the passage 11. The arm 23 is provided with an opening 24 adapted to align with the opening 18 of the nut 17 when the spring connector 21 is assembled with the handle in the manner described.

Numeral 25 denotes an insulating washer of shape to fit the recess 16, and said washer is provided with an opening 26 to align with the openings in the nut and in arm 23, already mentioned. When the insulating washer is assembled with the handle it lies in the recess 16 against the arm 23 of the spring connector 21.

Numeral 27 represents a second spring connector of L-shape, which may be a duplicate of the spring connector 21, including a long arm 28 and a short arm 29. The long arm 28 is adapted to enter the passage 12 and the short arm 29 is adapted to lie in the recess 16 and way 20 in the same manner that the arms of the spring connector 21 are fitted to the passage 11 and recesses 16 and 19. When the spring connector 27 is assembled with the handle, its short arm 29 lies within the recess 16 against the insulating washer 25, and said short arm is provided with an opening 30 corresponding with the opening 24. As will be more clear from Figs. 2, 5 and 6, the openings 24 and 30 are larger in diameter than is the opening 18 in the nut 17.

Numeral 31 represents a metal sleeve conducting member, which can be a piece of standard metal tubing. The sleeve 31 is of diameter to nicely fit in the recess 16 so that one of its ends is against the short arm 29 of the spring connector 27.

Numeral 32 denotes a rod or shank conducting member, which can be a piece of standard brass rod, having a head 33 of proper size and construction to contact with an element of a telephone jack or other plug receptacle, and numeral 34 indicates a bushing of insulating material upon said rod or shank, the bushing including an annular flange 35 adapted to lie against the inner face of the tip 33 of said rod or shank. The end of the rod or shank 32 opposite its tip 33 is, as shown, provided with a thread 36 adapted to engage the threaded opening 18 of the conducting nut 17. The diameter of the insulating bushing 34, adjacent the flange 35, is about equal to the internal diameter of the metal sleeve 31.

Assuming that the spring connectors, insulating washer, and metal sleeve have been associated with the plug handle in the manner described, the assembling of said plug is easily completed by inserting the rod or shank 32 through said metal sleeve and through the openings of the spring connectors and insulating washer and turning the thread of said rod or shank into the nut

17. This operation fastens all of the parts of the plug to the handle thereof, as is evident.

As disclosed more clearly in Fig. 2, the insulating bushing 34 enters the outer end of the metal sleeve to fix the relation of the sleeve and rod or shank, and the annular flange 35 of the bushing lies between the tip 33 of the rod or shank and the metal sleeve to insulate said rod or shank and sleeve conducting members from each other. The relation of the rod or shank and sleeve at their inner ends is fixed, as is obvious, by the fit of the metal tube in the recess 16 and the engagement of the rod or shank with the nut 17 of the handle. When the elements of the plug are assembled, the metal sleeve is accurately spaced and insulated from the shank and its associated tip.

The tip 33 of the rod or shank functions to hold the inner end of the metal sleeve in the recess 16 against the outer spring connector 29 thus holding said outer arm in engagement with the insulating washer 25, said washer in engagement with the inner spring connector 23, and said inner arm in engagement with the conducting nut 17. The insulating washer, naturally, holds the arms 23 and 29 of the spring connectors apart and insulates said spring connectors from each other. The recesses 16 and 20 of the handle portion position the arm 29 of the spring connector 27 so that the rod or shank 32 is clear of the wall of the opening 30 in said arm 29.

It will be evident that the metal sleeve 31 and spring connector 27 are in conducting engagement, while the rod or shank 32 engages the conducting nut 17 which in turn engages the spring connector 21. It will also be evident that the metal sleeve 31 and spring contact 27 are spaced from and insulated from the rod or shank 32, the nut 17, and the spring connector 21.

Numeral 37 represents cord tips adapted to be releasably held in the passages 11 and 12 by the arms 22 and 28 of the spring connectors in a manner which will be obvious.

What I claim is:

1. An electric plug comprising a sleeve contact, a tip contact, a rod connected to the tip contact and extending thru the sleeve, means for insulating said sleeve contact from the tip contact and rod, a one-piece handle of insulating material having a pair of passages for the reception of electrical conductors, a nut permanently embedded in the handle into which the end of the rod is adapted to be screwed, and insulated connectors associated with the tip and sleeve contacts and adapted to be detachably clamped between the nut and the sleeve contact and to engage the conductors when inserted in the passages.

2. An electric plug comprising a sleeve

contact, a tip contact, a rod connected to the tip contact and extending through the sleeve, means for insulating said sleeve contact from the tip contact and rod, a handle of insulating material having a pair of passages for the reception of electrical conductors, and insulated connectors associated with the tip and sleeve contacts and adapted to be detachably clamped between the insulating handle and the sleeve contact and to engage the conductors when inserted in the passage.

Signed at Bridgeport, in the County of Fairfield, and State of Connecticut, this 5th day of March A. D., 1925.

HENRY O. ENGSTROM.
